(57) **CLAIM**

The ornamental design for a portable, small scale indoor aquaponic system, as shown and described.

DESCRIPTION

FIG. 1 is a front perspective view of a first embodiment of a portable, small scale indoor aquaponic system configured in accordance with the present invention;

FIG. 2 is an exploded view thereof;

FIG. 3 is a cross-sectional view thereof, taken along line 3-3 of FIG. 4;

FIG. 4 is a top plan view thereof, not showing the grid-like support structure at the bottom of each tier for ease of illustration;

FIG. 5 is a front perspective view of a second embodiment of a portable, small scale indoor aquaponic system in accordance with the present invention;

FIG. 6 is an exploded view thereof;

FIG. 7 is a cross-sectional view thereof, taken along line 7-7 of FIG. 8; and,

FIG. 8 is a top plan view thereof, not showing the grid-like support structure at the bottom of each tier for ease of illustration.
